Specification for Design.

Patented July 26, 1921.

Application filed August 27, 1920. Serial No. 406,492. Term of patent 14 years.

To all whom it may concern:

Be it known that I, COURTNEY W. SHROPSHIRE, a citizen of the United States, residing at Birmingham, in the county of Jefferson and State of Alabama, have invented a new, original, and ornamental Design for Emblems, Badges, Buttons, Pins, Fobs, Rings, or like Articles of Manufacture, of which the following is a specification, reference being had to the accompanying draw-

ing, forming part hereof, wherein is shown a view in elevation of an emblem, badge, button, pin, fob, ring, or like article embodying my invention.

What I claim is:—

The ornamental design for an emblem, badge, button, pin, fob, ring, or like article of manufacture as shown.

In testimony whereof I affix my signature.

COURTNEY W. SHROPSHIRE.
